UNITED STATES PATENT OFFICE

FRANK C. PICKARD, OF ERIE, PENNSYLVANIA, ASSIGNOR TO THE STANDARD STOKER COMPANY, INCORPORATED, A CORPORATION OF DELAWARE

STOKER MECHANISM

Application filed May 25, 1929. Serial No. 365,878.

This invention relates to stoker mechanism and more particularly to the distributing member therefor, and the principal object of the invention is the provision of a novel 5 sectional distributor member that is provided with new and improved means for connecting the sections together.

Another object of the invention is the provision of a new and improved distributor 10 member having the portion that normally extends into the firebox of the locomotive entirely removable whereby the same may be readily replaced.

A further object of the invention is the 15 provision of a novel sectional distributor member that is provided with new and improved means for attaching the sections together and for securing the members in position, whereby the forward section or the entire member may be easily detached and readily removed.

A still further object of the invention is the provision of a sectional distributor member so constructed that only the forward section 20 will be exposed to the intense heat of the furnace, together with means for permitting the ready removal of said section.

Another object of the invention is the provision of a new and improved sectional distributor member that is cheap to manufacture, simple in construction, and one in which the end exposed to the heat of the furnace may be readily and easily replaced.

Other and further objects and advantages 35 of the invention will appear from the following description taken in connection with the accompanying drawings, in which

Fig. 1 is a vertical section of a portion of a locomotive and a stoker therefor, showing 40 my invention in position therein;

Fig. 2 is a section on line 2—2 of Fig. 1;

Fig. 3 is a perspective view of the rear section of the distributor member; and

Fig. 4 is a perspective view of the forward 45 section of the distributor member.

In the use of locomotive stokers, the forward ends of the distributor plates are subjected to the intense heat of the firebox and as a result they burn off or are damaged to 50 such an extent that they must be replaced

at intervals of from four to six weeks. Heretofore, it has been necessary to replace the entire plate which requires the services of two men for a considerable length of time to effect the changes.

The present invention seeks to remedy these difficulties by providing a sectional distributor plate in which the forward section may be readily and easily removed or replaced, the parts being so constructed that 60 they may be detachably hinged together whereby one man may replace a burnt-out section with a new one with a minimum amount of time and labor.

Referring now to the drawings wherein one 65 embodiment of the invention is shown, the reference character 10 designates a locomotive having the backhead 11 provided with the firedoor opening 12. The structure thus far described may be of the usual or any 70 well known construction, and further description or illustration is unnecessary.

A suitable stoker 13 is provided for supplying fuel to the locomotive. The stoker comprises a riser conduit 14 which extends 75 upwardly and is curved forwardly for delivering the fuel through the opening 12 onto a distributor plate 18. The conduit 14 is provided with a movable section 15 hinged at its lower portion as at 16 to the body of the 80 conduit. The upper portion of the section 15 cooperates with the firedoor 17 for forming a closure for the opening 12 when in the position shown in Fig. 1 of the drawings. Access may be had to the firebox for hand 85 firing by opening the door 17 and moving the section 15 rearwardly about its hinge 16.

A sectional distributor member 18 is provided for receiving the fuel conducted upwardly through the conduit 14. The distributor member 18 is preferably in the form of a sectional plate, and comprises a rear section 19 having an upper flat face 21 and a forward or removable section 22 having the flat face 23, which is adapted to align with 90 the corresponding face 21 of the rear section 19.

Suitable means are provided for rigidly attaching the rear section 19 of the distributor plate to the riser conduit 14. As shown, 100

the lower wall 24 of the conduit 14 is provided with a recess or cut-away portion 25, into which is adapted to project the reduced portion 26 of the rear section 19, as clearly shown in Fig. 2 of the drawings. A plurality of screws 27 is adapted to hold the parts in assembled relation.

Fuel projecting means, in the form of a steam nozzle 28 having a plurality of nozzle openings 29 therein, is clamped in position in a recess 31 between the bottom wall of the riser conduit and the rear section 19 of the distributor plate by the screws 27, which engage the bottom wall of the riser conduit and the reinforcing flange 33 on the distributor plate for holding the parts in assembled relation. If desired the rear section 19 of the distributor plate may be provided with a set screw 34, which engages the lower surface of the plate for engaging the lower marginal surface 35 of the door opening for constituting a seat for the distributor plate. This screw may be adjusted to compensate for slight variations in the dimensions of the different parts. The rear section terminates adjacent to the inner wall of the backhead, whereby it is protected from the heat of the fire-box.

Suitable means are provided for connecting the sections of the distributor member together. As shown, the rear section is provided with openings 36, 37, adjacent to the forward edge thereof, that portion of the upper flat face 21 between the openings 36, 37 and the forward edge thereof forming the pintles 38, 39, their lower surfaces being curved, as at 41, for this purpose. The forward section 22 of the distributor member is provided with hinge members 42, 43, which are curved for engaging the corresponding pintles 38 and 39. The parts are so constructed that the meeting edges of the two sections will form shoulders that engage after the manner of a butt hinge for limiting the downward movement of the front section below the plane of the upper surface of the rear section 19, but will permit the same to hinge upwardly and rearwardly for disengaging it from the rear section after which it may be removed by sliding the same rearwardly on the rear section. The upper or free ends of the hinge members 42 and 43 terminate in the plane of the upper surface of the section, whereby, when the sections are assembled, they will be flush with the upper surface of the rear section, as clearly shown in Figs. 1 and 2 of the drawings.

Suitable means are provided for supporting the front section while the same is being attached to the rear section. As shown, the rear section is provided with a forwardly extending projection or ledge 44, which is downwardly offset from the plane of the rear section to form a support, as shown in Fig. 3.

In attaching the forward section to the rear section, the front section is placed on the supporting ledge 44 at an inclination sufficient to permit the hinge members 42, 43, to engage the pintles 38, 39, after which, by means of a hook or the like, the said front section is lowered to position. The removal of the front section is accomplished with little difficulty, it being only necessary to reach through the opening 12 with a hook or bar and raise the front end of the forward section, turning it over onto the rear section. It can then be removed from the fire-box. If necessary the forward section can be removed and another inserted in its place without drawing the fire, thereby effecting a great saving of time in making replacements.

The projection or ledge 44 may abut the lower portion of the front section to assist in supporting the forward section, but since it merely forms a shoulder or abutment for this purpose it need extend into the fire-box only a short distance, and consequently is not likely to become hot enough to burn off.

The forward section 22 is provided with air passages 45, 46, extending horizontally therethrough. These passages align with an air passage 47 in the rear section.

The forward section 22 is provided with curved channels 48 for directing the fuel laterally, as is usual in such constructions.

I claim as my invention—

1. A distributor plate for stokers comprising a rear section having openings near its forward edge, that portion of said rearward section between said openings and said forward edge forming pintles, the lower portion of said pintles being curved, and a forward section provided with rearwardly extending hook members for engaging said pintles, the ends of said hook members being flush with the upper surface of said rear section when said sections are in alignment, said rear and forward sections being provided with means coacting to hold said sections in alignment.

2. In a stoker, a distributor plate comprising a rear plate section having an opening extending longitudinally thereof and a front section having an opening adapted to align with said first named opening when said sections are assembled in operative position, said rear and front sections each being provided with one element of a detachable hinging means cooperating to hingedly connect said rear and front sections, and an adjustable supporting member carried by said rear section and extending downwardly therefrom constituting a rest for said section.

3. As an article of manufacture, a forward section of a fuel distributor for stokers comprising a table having a flat top face indented on either side by laterally extending channels curving outwardly to the side edges of said table, hook members extending rearwardly

- and curving upwardly from the lower rearward edge of the table, the upper ends of said hook members being in the same horizontal plane with the top face of the table,
- 5 said hook members forming one element of a hinging means and a passage extending horizontally through said table beneath the top face thereof.
4. As a new article of manufacture, a rear section of a fuel distributor for stokers comprising a table having a flat top face, a flange extending downwardly from the rearward edge of said table, a tongue underlying said table extending forwardly beyond the forward edge thereof, the underside of said table near the forward edge thereof being provided with holes, that portion of said table included between its forward edge and said holes having arcuate shaped bottom surfaces 10 and forming one element of a pivotal connecting medium.
5. As a new article of manufacture, a forward section of a fuel distributor for stokers comprising a table having a flat top face indented on either side by laterally extending channels curving outwardly to the side edges of said table, hook members extending rearwardly and curving upwardly from the lower rearward edge of the table, and passages extending horizontally through said table beneath the top face thereof.
6. In a stoker, a member for receiving fuel about to be spread over a fire comprising separable rear and front plate sections, the rear section having means underlying the front section restraining downward movement of the same, said rear section having a pintle formed therewith adjacent its forward edge below its fuel receiving surface and 15 said front section being provided with a rearwardly extending hook member for engaging said pintle.
7. As an article of manufacture, a rear section of a fuel distributor for stokers comprising a table having a flat top face, a flange extending downwardly from the rearward edge of said table, and a tongue underlying said table intermediate the sides thereof and extending forwardly beyond the forward edge of said table, the forward portion of said table being provided with an opening on each side of said tongue, that portion of the table between said openings and its forward edge forming pintles constituting one element 20 of a hinging means, the lower portion of said pintles being curved.
8. In a stoker, a distributor plate comprising a rear section and a front section, said rear and front sections each being provided with one element of a hinging means for connecting the adjacent edges of said sections together, the rear section having a tongue underlying said front section, said hinging means coacting with said tongue to prevent 25 the downward movement of said front section below the plane of said rear section and disposed with no part thereof protruding above the upper surface of either of said sections.
9. A distributor plate for stokers comprising a rear section and a front section, said rear and front sections each being provided with one element of a hinging means for detachably connecting said sections together, said hinging means being arranged with no part thereof protruding above the upper surface of either of said sections, and said sections being provided with cooperating shoulders for limiting the downward movement of said front section.
10. In a distributor plate for stokers, a rear section and a forward section, said rear and forward sections each being provided with one element of a hinging means coacting with each other for detachably, pivotally connecting said sections together, said rear section having a tongue underlying said plate intermediate the sides thereof and extending forwardly beyond the forward edge of said rear section.
11. In combination, a fuel riser conduit and a distributor plate for stokers, said plate comprising a rear section and a forward section, said rear section having means underlying said forward section restraining downward movement of the same and being provided with means for attachment to said riser conduit, said rear and forward sections each being provided with one element of a hinging means cooperating to hingedly connect said forward and rear sections, said hinging means being arranged with no part thereof protruding above the upper surface of either of said sections.
12. In combination, a stoker riser conduit and a distributor plate for receiving fuel discharged from said conduit, said plate comprising a rear section and a forward section, said rear section having means underlying said forward section restraining downward movement of the same and being provided with a flange arranged to receive means for detachably securing it to said conduit, said rear and forward sections each being provided with one element of a hinging means cooperating to hingedly connect said forward and rear sections.
- In testimony whereof I affix my signature.
FRANK C. PICKARD.
